SAMUEL E. SPERRY, OF WOODHAVEN, NEW YORK, ASSIGNOR TO INTERTYPE CORPORATION, OF BROOKLYN, NEW YORK, A CORPORATION OF NEW YORK.

SLUG-TRIMMING KNIFE FOR LINE-CASTING MACHINES.

1,426,231.

Specification of Letters Patent. Patented Aug. 15, 1922.

Application filed July 30, 1921. Serial No. 488,592.

To all whom it may concern:

Be it known that I, SAMUEL E. SPERRY, a citizen of the United States, residing at Woodhaven, in the county of Queens and 5 State of New York, have invented new and useful Improvements in Slug-Trimming Knives for Line-Casting Machines, of which the following is a specification.

The present invention relates to improvements in line casting machines, and more 10 especially to those of the linotype class, wherein type slugs are cast from lines of matrices and these slugs are ejected from the mold and forced through an appropriately measured space between a pair of knives 15 which trim the flat sides of the slugs to the proper thickness to conform with the size of the type in process of production.

Slug-trimming knives, as heretofore used 20 generally, embodied two knife blades, one blade being usually fixed in relation to one side of the mold, and the other knife blade being adjustable relatively to the first-mentioned knife blade, to provide a space between the blades which will conform with 25 the body size of the type to be produced, and means of various kinds have been employed for adjusting the movable knife blade to conform with type of different 30 body sizes. The patent granted to T. S. Homans No. 1,202,720 dated October 24, 1916, shows and describes knife-adjusting means which is capable of setting the movable knife blade with accuracy.

Practice has demonstrated, however, that 35 in using slug trimming knives of the type generally employed, the pressure or thrust imposed on the relatively movable knife blade incident to the forcing of the slug 40 from the mold and through the space between the knife blades acts to tilt or deflect the relatively movable knife blade, in consequence of which the leading edge of this blade is caused to gouge into the adjacent 45 flat side of the slug undergoing trimming and this results in an imperfect trim. Such bending or deflection of the relatively movable knife blade has proven unavoidable in trimming knives as heretofore used, owing 50 to the necessity of providing an adjustment for the movable knife blade which will provide for the trimming of type slugs varying from 6 point to 42 points in body sizes, the relatively movable or adjustable knife 55 blade, in trimming knives as heretofore constructed, being fixed to a supporting plate,

which plate in turn was guided to slide on the knife block to which the relatively fixed knife blade was secured, and this knife block being necessarily cut away to permit 60 the passage of slugs of the largest body sizes to the collecting galley, in consequence of which the relatively movable or adjustable knife blade necessarily overhung the cut-away portion of the knife block and was 65 subject to bending or deflection under the thrust of the slug.

The present invention provides a novel 70 and improved mounting for the relatively movable or adjustable knife blade, whereby the difficulty above referred to is avoided and a perfect trimming operation may be accomplished, these results being attained by so mounting the relatively movable or adjustable knife blade that tipping, bending or 75 other dislocation thereof under the thrust of the slug is effectively prevented.

To these and other ends, the invention 80 consists in certain improvements and combinations and arrangements of parts, all as will be hereinafter more fully described, the features of novelty being pointed out particularly in the claims at the end of the specification.

In the accompanying drawing:—

Figure 1 represents a section taken transversely through a slug trimming device constructed in accordance with the preferred embodiment of the invention; and

Figure 2 is a perspective view of the same 90 with the relatively fixed knife blade omitted.

The present invention is applicable generally to slug trimming knives of the various types heretofore known or used, independently of the particular means employed for adjusting the knife to conform with type of different body sizes. In the present instance the invention is shown applied to a slug trimming knife of the kind shown and described in the Homans patent hereinbefore referred to. It is to be understood, however, that the invention is not restricted to the particular construction shown, as equivalent constructions are contemplated and these will be included within the scope of the claims.

In the present instance, 1 designates a portion of the vice frame of a machine of the linotype class, the same having one of the slug trimming knives 2 fixed thereon, and 3 designates the knife block which is fixed to the vice frame. The adjustable or

movable slug trimming knife 4 is controlled with respect to its distance from the cooperative knife 2, by a relatively large screw 5 which is threaded exteriorly and fits 5 within a similarly threaded ring or nut 6, an adjusting handle 7 being connected to the screw 5 by the locking screw 8 and having circumferentially spaced notches 9 in its periphery to cooperate with a locking 10 dog 10, by which the degree of rotation of the screw 5 may be determined.

The leading edges 2^a and 4^a of the knives first engage the slug as the latter is ejected edgewise from the mold and pushed through 15 the space between the knives by the slug ejector, the trimmed slug passing on to the collecting galley. In order to enable the slugs of larger thicknesses to pass from the trimming knives to the galley, it is necessary to form the knife block with a recess 11 which underlies the movable or adjustable knife 4. A guiding blade 12 may be attached to the movable knife 4 to act as a guide for the slug in passing from the trimming knives to the galley.

According to the present invention, the knife block 3 is formed beyond the opposite ends of the recess 11 with supports 13 and 14 which are preferably in substantially the 30 form of rails extending longitudinally of the direction of adjustment of the knife 4, as shown, and the ends of the adjustable knife 4 are extended to bear on these supports or rails. It will be understood that the recess 35 11 is of a length sufficient to accommodate slugs of the greatest length and that these knife supports or rails 13 and 14 are spaced apart for a distance greater than the length of the longest slugs. Preferably, the adjustable knife 4 is formed with extensions 40 15 and 16 of reduced height and these extensions which project beyond the ends of the recess or cut-away portion 11 overlie and bear upon the supports 13 and 14 on the 45 knife block. The adjustable knife 4 is operatively related to the adjusting screw 5 preferably through the medium of a pair of longitudinally spaced screws 17 which bear against a thrust ring 18, the latter in 50 turn bearing against the end of the adjusting screw 5 adjacent to the knife 4. The adjustable knife 4 is held in properly seated relation with the supporting and guiding rails 13 and 14 and also in proper relation 55 with the adjusting screw 5 by a tension spring 19, one end of which is attached to a hook or projection 20 fixed to the knife 4 preferably at or substantially midway of its length, but below the level of the supports or rails 14, and the opposite end of 60 this spring is attached to an arm or bracket 21 which is fixed, as by the screws 22, to the knife block and projects through a central opening in the adjusting screw 5 to the 65 thrust ring 18.

The spring 19 acts diagonally or in an inclined direction relatively to the knife-engaging surfaces of the supports or rails 13 and 14, and hence it will cause the adjustable knife 4 to bear constantly and 70 evenly on these supports or rails, irrespective of the various adjustments that may be made to vary the distance of the knife 4 from the knife 2, and the spring will also act to maintain the screws or studs 17 on the knife 75 4 in engagement with the thrust ring 18 and to maintain this thrust ring in engagement with the adjacent end of the adjusting screw 5. The strength of the spring may vary to some extent, due to variations in 80 the distance of the knife 4 from the knife 2, but the spring will always function to maintain the knife 4 in properly seated relation with the supports or rails on the knife block and to maintain correct operative relation between the knife 4 and the adjusting screw 5. By this arrangement, the leading edges 2^a and 4^a of the knives will be 85 capable of sustaining the thrust imposed upon them by the slug, as the latter is 90 ejected from the mold and forced through the space between the knives, without causing tipping, bending or other deflection or dislocation of the knife 4 relatively to the knife block, and this result is not impaired 95 by the different adjustments of the knife 4 to accommodate slugs of different body sizes.

Usually the depth of the knives increases toward one end thereof to produce a progressive engagement of the leading edges of the knives with the slug. Figure 2 shows the knife 4 as increasing in depth toward its lower end. The resulting end thrust produced on the knife 4 by reason of its tapered form and also the weight of this knife, as well as the lateral thrust imposed thereon, are sustained by the lower support or rail 14 which, as shown, is preferably shaped to fit against the two adjacent sides of the 110 notch or recess in this end of the knife and this support or rail thus functions to prevent displacement of the adjustable knife in two directions. It will be understood that in the construction hereinbefore described, 115 no means other than the spring 19 is required to maintain the adjustable knife 4 in properly seated relation with its supports or rails and in proper operative relation with the adjustable screw, and that this spring will 120 not only function to produce these results, but it will also eliminate any lost motion or play between the parts of the trimming device, and hence accuracy in the setting of the knives and correct performance of the trimming operation are attained.

I claim as my invention:—

1. A slug-trimming means for line casting machines comprising a support, cooperative knives one of which is adjustable relatively to 130

- 5 said support in a direction toward and from the other knife, the support having rests on which the adjustable knife bears at its respective ends and which rests extend in advance of the edge of the adjustable knife, and means for holding the adjustable knife in engagement with said rests.
- 10 2. Slug-trimming means for line casting machines comprising a support, cooperative knives one of which is adjustable relatively to said support in a direction toward and from the other knife, the support having portions on which the respective ends of the adjustable knife bear slidably and which portions extend in advance of the edge of the adjustable knife, and a spring operative to maintain said adjustable knife in correct bearing engagement with said portions of the support.
- 15 20 3. Slug-trimming means for line casting machines comprising a support, cooperative knives one of which is adjustable relatively to said support in a direction toward and from the other knife, said support having spaced rails on which the adjustable knife directly behind the trimming edge thereof bears throughout the range of adjustment of said adjustable knife, and a spring acting on the adjustable knife in a direction oblique to the knife-engaging portions of said rails and operative to maintain the adjustable knife in correct bearing engagement with said rails throughout the range of adjustment of said knife.
- 25 35 4. Slug-trimming mechanism comprising cooperative knives one of which is adjustable relatively to the other, and supports extending in advance of the edge of the adjustable knife and on which the opposite ends of the adjustable knife bear, said supports being spaced apart at a distance greater than the length of the longest slug to be trimmed and defining the length of the slug trimming passage between the knives and being located in a plane offset relatively to the trimming edges of the knives.
- 40 50 5. Slug-trimming mechanism comprising an adjustable trimming knife, abutments to sustain thrust of said knife in two directions, and a spring mutual to and acting to hold the knife against said abutments.
6. Slug-trimming means comprising a support having a recess for the passage of a trimmed slug therethrough and provided with bearing surfaces beyond and defining the ends of the recess, a knife overlying said recess and having its ends extended and slidably bearing on said bearing surfaces on the support, said bearing surfaces extending in advance of the edge of said knife and means acting to maintain said ends of the knife in engagement with the bearings on the support. 55
7. Slug-trimming means comprising a support having a passageway for a trimmed slug and provided with bearing rails located beyond the respective ends of said passageway, a knife to extend longitudinally across said passageway and having its ends extended to overlie and bear on said rails, and a spring 65 acting in a direction oblique to the knife-bearing surfaces of said rails and operative to hold the ends of the knife against the rails. 70
8. In slug-trimming means, a support having a recess to receive trimmed slugs and provided with bearing surfaces beyond the respective ends of the recess, a trimming knife to extend across said recess and having its ends extended beyond the ends of the recess and notched to receive and bear against said surfaces on the support, and means acting to press and hold the knife against said bearing surfaces. 75
9. In slug-trimming means, the combination of a support having relatively spaced bearing surfaces thereon, a knife having its ends adapted to bear on said surfaces, means for adjusting the position of the knife on said bearing surfaces, and a spring acting in an inclined direction relatively to said bearing surfaces and operative to hold the ends of the knife against the respective bearing surfaces and to hold the knife against said adjusting means. 80 85 90 95

In testimony whereof I have hereunto set my hand in presence of two subscribing witnesses.
